UNITED STATES PATENT OFFICE.

EMIL R. BITTNER, OF VICTORIA, TEXAS.

LIQUID-FUEL BURNER.

1,342,526.

Specification of Letters Patent. Patented June 8, 1920.

Application filed January 31, 1919. Serial No. 274,226.

To all whom it may concern:

Be it known that I, EMIL R. BITTNER, a citizen of the United States, residing at Victoria, county of Victoria, State of Texas, 5 have invented certain new and useful Improvements in Liquid-Fuel Burners, of which the following is a specification.

This invention relates to improvements in liquid fuel burners.

One of the objects is to produce a burner adapted to generate gas from liquids rich in hydro-carbons and consume the same in an economical manner.

And finally to produce a heating system, 15 adapted for use in private or public buildings, that requires practically no labor or supervision, the same operating continuously so long as a fuel supply is maintained.

These and other objects are attained by 20 the novel combination and construction of parts and principles hereinafter described, and shown in the accompanying drawings, forming a material part of this disclosure, and in which:—

Figure 1 is a longitudinal view of a heater made in accordance with the invention, partly in elevation and partly in section.

Fig. 2 is a transverse sectional view of the same taken on the line 2—2 of Fig. 1, the 30 support for the nipple being omitted.

Fig. 3 is an enlarged vertical sectional view taken through one of the burner heads.

Fig. 4 is a top plan view of the same.

Referring now more particularly to Figs. 35 1 and 2 of the drawings, the burner shown is comprised of a pair of rigid end plates 10 and 12 joined by a thin deflecting or cover plate 14.

Also connecting between the end plates, 40 near the bottom is concavo-convex plate 16, having thickened edges 17, forming a trough-like receptacle for purposes further indicated.

Liquid fuel is supplied to the burner 45 through the feed pipe 20, having a control valve 21, engaged with the tubular element 22 of the heater which passes through the end plate 12, below the cover 14, and is engaged at its opposite end with an elbow 23

50 having a plugged opening 24.

Engaged in the vertical opening of the elbow is a nipple 26 held by a clip 27 to the end plate 10, and engaging the nipple is another elbow 28 similar to the elbow 23, 55 both of which are partially contained in a recess 29 formed in the plate 10.

Engaged in the other opening of the elbow 28 is another tubular element 32, forming a U bent with the tube 22, and extending out through the end plate 12, the 60 end of the tube being covered by the flange cap 33.

Extending diagonally downward from bases 34 formed with the tube 32, into recesses 35, are two pipes 36, screw-threaded 65 into valve casings 38 set in the lower portions of the recesses 35, in which they are held by the cover plate 39. These valve casings 38 are hollow and have outwardly extending hubs 40 receptive of the screw-threaded stems 41, having on their extending ends hand wheels 42, while the inner ends of the stems are formed into conical valves 43, extending through the oppositely disposed hubs 44 of the valve casings 38, 70 and are adapted to the valve seats 46 formed in blocks 45 at the ends of the hubs 44.

Engaged exteriorly of the hubs 44 and adapted to retain the blocks 45 in position, are other horizontal tubular elements or cylinders 48 having plugs 49 in their opposite end which rest in recesses 50 formed in the end plate 10.

Set radially in the cylinders 48 are two rows of spaced burner heads 52, the inner 85 row of each cylinder being directed toward the tube 32 and interposed therebetween is a flame breaker comprising a bar 55 on which are spaced a plurality of thin plates 56, the upper wider ends being closely adjacent to 90 the tube 32, to which the bar 55 is parallel, it being held direct in the end plate 12 at one end and in a bracket 57 at the other, the bracket being attached to the plate 10.

The burner heads or tips 52 are each 95 formed with a screw-threaded stem 60 containing a conical opening 61 in communication at its base with the interior of the cylinder 48, while its upper end enters a mixing chamber and diffuser 62 having a plurality 100 of small perforations 63 in its top leading to the atmosphere formed at the apices of obliquely disposed conical passages 65 formed in the beveled annular bases 66 of the tips.

In operation liquid fuel being supplied through pipe 20 from any suitable source the valve 21 is turned on until it flows out of the tips 52 into the trough or pan 16 and there ignited. The heat thus generated soon 110 causes the liquid in the burner tubes 48 to gasify and eventually a similar effect takes

place in the tube 32 so that by adjusting the valve hand wheels 42 gas may be delivered to the burner tips in desired quantity, the pan 16 being used only while starting the burner into operation.

Having thus described my invention what I claim as new and desire to secure by Letters Patent is:—

1. A fuel oil burner comprising a pair of horizontal tubes, disposed one over the other, a U-shaped bend connecting at one end therebetween, means for controlling the inlet of fuel to the upper of said tubes, a pair of divergent pipes engaged with the lower of said tubes, valve casings engaged with the lower end of said pipes, control valves in said casings, longitudinally extending cylinders engaged in said heads, a plurality of burners in said cylinders, a bar extending below said tubes and a plurality of plates secured to said bar over said burners whereby heat may be converged thereto.

2. A fuel oil burner comprising a pair of horizontal tubes, connections therebetween at one end, controlling means on the uppermost of said tube, a pair of cylinders below said tubes and connections between the lowermost of said tubes to said cylinders, con-

trolling means in said connections, a plurality of burners extending at intervals in offset rows in said cylinders, and means below said cylinders adapted to receive liquid fuel from said burners.

3. A fuel oil burner comprising a pair of rigid end plates, a concave starting fan secured between said end plates, a pair of cylinders supported by said end plates spaced above said concave starting fan, a plurality of burners arranged on offset rows in said cylinders, and means for directing the flame from said burners.

4. In a fuel oil burner, the combination with one or more cylinders and a plurality of burners connected therewith, said burners comprising a conical tip having a central discharge passage for the fuel, and a plurality of conical air inlets spaced around said central passage in said tip, a mixing chamber formed in the uppermost portion of said tip, said air inlets and said discharge opening into the bottom of said chamber closely adjacent to each other.

In testimony whereof I have signed my name to this specification this 1st day of October, 1918.

EMIL R. BITTNER.
